UNITED STATES PATENT OFFICE

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS

DESIGN FOR A PLATE OR ANALOGOUS ARTICLE

Application filed May 12, 1930. Serial No. 35,589. Term of patent 14 years.

To all whom it may concern:

Be it known that I, HAROLD E. NOCK, a citizen of the United States, residing at Newburyport, in the county of Essex and Commonwealth of Massachusetts, have invented a new, original, and ornamental Design for a Plate or Analogous Article, of which the following is a specification, reference being had to the accompanying drawing, forming a part thereof.

In the drawing, Figure 1 is a plan view and Fig. 2 is a view in elevation of a plate showing my new design.

The dominant feature of the design consists in the marginal spot ornamentations.

I claim:

The ornamental design for a plate or analogous article, substantially as shown and described.

HAROLD E. NOCK.
